UNITED STATES PATENT OFFICE.

WILLIAM HOWARD FRANKLAND, OF JACKSON, TENNESSEE.

SHARPENING DEVICE.

1,417,158.

Specification of Letters Patent. Patented May 23, 1922.

Application filed November 2, 1921. Serial No. 512,292.

To all whom it may concern:

Be it known that I, WILLIAM H. FRANKLAND, a citizen of the United States, and a resident of Jackson, in the county of Madison and State of Tennessee, have invented certain new and useful Improvements in Sharpening Devices; and I do hereby declare the following to be a full, clear, and exact description of the invention, such as will enable others skilled in the art to which it appertains to make and use the same.

This invention relates to improvements in sharpening devices and more particularly to such as are employed for sharpening knives,—one object of the invention being to provide a simple structure which may be applied to a table or other support and be operable effectually to sharpen the full length of a knife blade.

A further object is to provide a knife sharpener adaptable for domestic use, which shall be cheap to manufacture but which shall be operable to effect uniform bevels at respective sides of the edge portion of the blade and thus insure a straight and uniform cutting edge.

With these and other objects in view, the invention consists in certain novel features of construction and combinations of parts as hereinafter set forth and pointed out in the claims.

In the accompanying drawings, Figure 1 is a view illustrating my improved sharpener and the manner in which the same is used. Figure 2 is a sectional view of one of the sharpening cones. Figure 3 is a detail view of the swiveled guide member, and Figure 4 is a plan view of the base member.

The base 1 of the device may be conveniently made of metal and provided with a spring arm forming a clamp 2 to hold the device in place on a table or other support. The base 1 is provided with three aligning sockets or holes 3, 3 and 4. Each of the sockets 3 receives the lower end of a vertical spindle 5 which may be secured therein. Vertically disposed cones 6 of carborundum or other abrading material are mounted on the respective spindles 5 so that the larger ends of said cones may rest upon the base 1. The upper ends of the spindles 5 pass through holes near respective ends of a cross-bar 7 and may be headed at their up-

per ends. The lower end portions of these spindles are threaded for the reception of nuts 8 which bear against the under portion of the base and by means of which the cones may be clamped in place. It is apparent that by loosening these nuts, the cones can be turned to present fresh surfaces to the knife to be sharpened and thus prevent excessive, uneven wear on the cones.

The intermediate socket 4 receives the lower end of a swiveled guide member 9, the upper end of the latter being freely mounted in a hole centrally between the ends of the cross-bar 7. The swiveled guide-member 9 may be conveniently made in two parts as indicated in Figure 3 and so formed as to provide a vertical slot 10 to receive and guide the knife 11 to be sharpened as indicated in Figure 1.

It is evident that by moving the knife longitudinally through the slotted guide-member 9 and between the cones 6, the edge portion of the knife will be beveled at respective sides thereof so as to produce a straight and uniform cutting edge and by shifting the knife and guide-member, the edge portion of the knife may be effectually sharpened from one end to the other thereof.

Having fully described my invention what I claim as new and desire to secure by Letters-Patent, is:

1. In a sharpener, the combination with a base and a cross-bar, of conical sharpening members disposed between the same and spaced apart, and a swiveled guide mounted between said sharpening cones.

2. In a sharpener, the combination with a base and a cross-bar, of two sharpening cones mounted between the same and spaced apart, and a slotted guide disposed between said cones and swiveled at its respective ends in said base and cross-bar.

3. In a sharpener, the combination with a base and two spindles attached to said base and projecting therefrom, cones mounted on said spindles, a cross-bar through which said spindles pass, and nuts threaded on the lower end portions of said spindles, of a slotted guide swiveled in said base and cross-bar intermediate of said cones and parallel with the axes of the latter.

4. In a sharpener, the combination with a base having three aligning sockets and pro-

vided with clamping means for attaching said base to a support, of spindles secured to two of said sockets, sharpening cones mounted on said spindles, a cross-bar connecting said spindles, and a slotted guide swiveled in said base and cross-bar and disposed between said cones.

In testimony whereof, I have signed this specification in the presence of two subscribing witnesses.

WILLIAM HOWARD FRANKLAND.
